UNITED STATES PATENT OFFICE.

LAURITZ W. ANDERSEN, OF WATERBURY, CONNECTICUT.

SHADE HOLDER.

Application filed February 6, 1922. Serial No. 534,458.

To all whom it may concern:

Be it known that I, LAURITZ W. ANDERSEN, a citizen of the United States, residing at Waterbury, in the county of New Haven 5 and State of Connecticut, have invented a certain new and useful Improvement in Shade Holders, of which the following is a full, clear, and exact description, reference being had to the accompanying drawings.

This invention relates generally to shade holders and more particularly to a device for holding a silk or parchment shade in a downward or suspended position around an 15 incandescent lamp.

The object of the invention is to provide an exceedingly cheap and simple form of holder which can be quickly and easily attached to or detached from the ordinary 20 lamp socket and which will securely hold the shade after the same has once been connected thereto.

Another object of the invention is to provide a device of this character from which 25 one shade can be quickly and easily removed and another shade substituted when desired.

With these various objects in view the invention consists in the novel features of construction hereinafter fully described 30 and pointed out in the claims.

In the drawings forming part of this specification, Fig. 1 is a view showing the practical application of my invention, the shade holder being shown in elevation and 35 the shade in section; Fig. 2 is an inverted perspective of the device; and Fig. 3 is a sectional view of the shade holder and shade carrying frame.

In the practical embodiment of my invention I employ a collar 10 preferably formed with an inturned flange 10^a, said collar being slotted at 10^b to provide a plurality of resilient members 10^c and this slotted portion is grooved as shown at 10^d 40 in order to receive the bead of the ordinary incandescent lamp socket.

Surrounding this resilient collar which constitutes a socket receiving member, is a sheet metal band 11 flanged as shown, that 45 is, one portion 11^a of said band being vertical and the lower portion 11^b thereof obliquely flared thereby providing an annular shoulder upon which the inner ring 12 of the frame of the shade is adapted to rest, the 55 outer ring 13 of the shade frame being connected directly to the shade 14 and the outer

ring of the frame is connected to the inner ring by means of a plurality of arms 15. The inner and outer frames and arms of the shade frame are all constructed of wire of 60 suitable dimensions.

The band 11 is also connected to the collar 10 by means of right angular shaped wire arms 16. The upper portion of the band 11 is formed with a plurality of integral 65 tongues 17, said tongues being punched from the vertical portion of the band and are adapted to be turned down over the inner wire ring of the shade frame as most clearly shown, thereby securely connecting the shade 70 to the holder.

When it is desired to connect the shade to the lamp in the position indicated, it is only necessary to snap the collar over the lower 75 end of the socket and the connection of the shade to the socket is complete.

When it is desired to remove the shade from the lamp it is only necessary to spring the collar away from the lamp socket, it being understood of course, that the incandescent lamp is removed from the socket when the shade holder is being attached to or detached from the said socket.

When it is desired to remove the shade from the holder, it is only necessary to bend 85 back the tongues so as to release the inner ring of the frame, and the frame can then be disconnected from the band and a new shade and frame substituted and connected when desired.

It will thus be seen that I provide an exceedingly cheap and simple construction of shade holder and one which will securely hold the shade in proper position when once 90 adjusted.

Having thus described my invention, what I claim is:

1. A device of the kind described comprising a resilient collar, a band surrounding said collar and arms connecting said collar and band, said band having tongues punched therefrom.

2. The combination with a shade having a wire ring, of a flanged sheet metal band supporting the wire ring, a resilient collar 105 and arms connecting said collar and band, said flanged band having integral tongues for engaging the wire ring of said shade and securing the same in position.

3. The combination with a resilient collar 110 adapted to receive a socket, of a flanged band surrounding said collar and connected

thereto, said band having bendable tongues punched therefrom, a ring constituting a part of a shade frame and adapted to rest upon the flanged band and be engaged by 5 said tongues.

4. A device of the kind described comprising a socket receiving member, a band having a vertical portion and an outwardly extending portion providing a supporting shoulder, one portion of said band having 10 tongues punched therefrom, and arms connecting the socket receiving member with said band.

5. The combination with a socket receiving member, of a band comprising a vertical 15

portion and an outwardly flared portion, the vertical portion having integral tongues punched therefrom, arms connecting the socket receiving member and band and a shade frame comprising an outer ring and 20 an inner ring and connecting arms, the inner ring of said frame being adapted to rest upon the band, the tongues of said band being adapted for engagement with the inner ring of the frame, to connect the same to the 25 band.

In testimony whereof, I hereunto affix my signature.

LAURITZ W. ANDERSEN.
